(57) **CLAIM**

The ornamental design for a fishing reel bridge portion, as shown and described.

DESCRIPTION

FIG. 1 is a perspective view of the fishing reel bridge portion in accordance with our new design;

FIG. 2 is another perspective view of the fishing reel bridge portion in accordance with our new design;

FIG. 3 is a top plan view of the fishing reel bridge portion in accordance with our new design;

FIG. 4 is a bottom plan view of the fishing reel bridge portion in accordance with our new design;

FIG. 5 is a first side elevation view of the fishing reel bridge portion in accordance with our new design;

FIG. 6 is a second side elevation view of the fishing reel bridge portion in accordance with our new design;

FIG. 7 is a front elevation view of the fishing reel bridge portion in accordance with our new design; and,

FIG. 8 is a rear elevation view of the fishing reel bridge portion in accordance with our new design.

The broken line showing environment (the remaining structure of the fishing reel) in the Figures is for illustrative purposes only and forms no part of the claimed design.
